FOLDING BEAUTY-HEALTH BOARD

Amy Burkett and Georgie V. Reager,
Greene County, Mo.

Application March 4, 1946, Serial No. 651,832

1 Claim. (Cl. 311—8).

1

This invention relates to improvements in furniture, and more particularly to body manipulating tables and for benches.

One of the objects thereof is to provide a simple, efficient and inexpensive device of this character which is adapted to for especial use in connection with physical culture, chiropractic, osteopathic and body invigorating exercises and the like.

Another object thereof is to provide a table or bench for use in correcting defects in posture, nervous disorders which muscular massaging and manipulation can correct, and contortional movements of bodily limbs and muscles which are found conducive in the promotion of good health.

A further object of this invention is to provide a form of table or bench characterized by the circumstance that it is normally held at a horizontal level, but can instantly be converted into a table or bench with an inclined top for the purpose of raising one portion of the body of the occupant thereon with respect to the other part of the body.

A still further object thereof is to provide a device of the character described, means for raising and lowering one end of the table or bench with respect to the other, in order to impart postural deviations to the manipulatable parts of the human anatomy recumbent thereupon.

A further object thereof is to provide, in a device of this character, means for supporting a table or bench in varying inclinations by resorting to actuating means which travels along the bottom of the table or bench top.

A further object thereof is to provide in a device of the character described, means for folding the top so as to form a small table or bench useful for other purposes in the home or office.

A still further object thereof is to provide, in a device of the kind described, means for folding the legs up against the top in order to lessen the space required for transportation or storage when not in use.

With the above and other objects in view, our invention consists in the arrangement, combination and details of construction disclosed in the drawings and specifications, and then more particularly pointed out in the appended claim.

In the drawings:

Figure 1 is a side elevation, partly in section, of one form of our invention.

Figure 2 is a fragmental bottom plan view of the table top.

Figure 3 is a cross sectional view of our invention.

2

Figure 4 is a longitudinal sectional elevation of a modification of our invention, and

Figure 5 is a fragmental perspective view of said modification.

5 In the following description which is merely illustrative of our invention it will be understood that wherever the word "table" is used, it is intended to refer interchangeably to a bench or the like as well.

10 The table as disclosed, comprises a top 10 in connection with which is a false top member 11 spaced below therefrom by means of oppositely arranged bars 21 and 22 secured to false top 11. The table tops are supported at opposite ends by 15 two sets of legs; one pair being rigid, designated 15 and 16 for holding at an elevation one end of the table. The table top 11 is hingedly mounted by means of hinge plates 13 upon pintles 12, secured with hinge plates 14 to the upper ends 20 of rigid legs 15 and 16, to thereby permit the false top 11 to fold down upon the hinges just mentioned. Between the parts 10 and 11 is a space 17, in which extension top member 27a and brace bars 18 and 19 are adapted to slide.

25 The brace bars 18 and 19 joined together by cross bar 25 form an extension brace for member 26 hinged at 27 to the table top 10 so as to lie flush with the latter when this member is folded back on brace bars 18, 19 and 25, as shown in

30 Figure 1. There is another slidable panel 27a at the rear of the table which is arranged to operatively slide in the space 17 rearwardly of table top 10. Marginally depending from opposite sides of table top 10 are side bars 20, joined at each end 35 by similar bars (not shown) with openings therein arranged so as to permit the free operation of panel 27a and brace bars 18 and 19, to form a frame to conceal the operating mechanism.

We provide, for supporting the other end of the 40 table with reference to the legs 15 and 16, a pair of collapsible legs 32 and 33 hingedly mounted at their lower ends, by hinge plates 12a to pintles 14a in hinge plates 13a which are attached to leg stands 47, resting upon the same surface upon 45 which rest the rigid table legs 15 and 16. The upper end of the collapsible legs 32 and 33 are designed to have a pivotal coupled relationship to the table or bench structure thereabove. For this purpose use is made of a pair of lever arms 28 and 29 in connection with each of the collapsible legs 32 and 33. The upper ends of these legs are suitably slotted so that the lower ends of these arms 28 and 29 may swing therein, being pivoted, for this purpose, upon pins 30 secured in said legs.

50 There are rollers 35 journaled upon pins 34

secured into the upper ends of each pair of arms 28 and 29, which rollers run upon tracks 36 spaced parallel beneath false top 11 by the offset ends 37 which are secured by fasteners 38 to the ends of this part. In this way the coupling arms 28 and 29 are substantially hung upon the tracks, while beneath these tracks a separate pinion 49 is mounted for rotation upon a pin 41, also secured in each pair of arms 28 and 29 of the legs 32 and 33 respectively. These pinions mesh with racks 39 formed longitudinally upon the under sides of the tracks 36.

For the purpose of providing a rigid under framework for the table, it is contemplated that the leg stands 47 be braced and supported directly by means of such devices as tie bar 44. The rigid legs 15 and 16 are also braced by tie bars. The rigid legs 15 and 16 are braced to leg stands 47 by tie rod 48, which has oppositely pitched threads 45 at opposite ends thereof which are tapped into the tie bars respectively at 46. This tie rod 48 may freely be adjusted or removed by turning it, and to this end a polygonal wrench head 48a is provided between the ends of the tie rod.

Secured overlappingly upon the top 10 and extensible panel 26 thereof is a continuous corrugated quilt 43.

The slideable bracing member, composed of the bars 18, 19 and 25, when closed lies inside of the table or bench proper. Panel 26 may be folded back into surmounted relation upon top 10 in an obvious manner. Rear panel 27a may also be slid into space 17 so as to be closed inside of the table or bench proper. With the parts in this position, and with all legs in firmly upright position, as shown in Figure 1, the top will assume a horizontal level, and even keel, and forms a table or bench, useful and attractive. When tie rod 48 is removed the legs may be folded up against the board for greater convenience and to save space in storage or shipping.

In operation the extended table or bench top may be tilted to incline from high at one end to low at the other, as follows:

When it is desired to posture a person thereupon bracing member 18, 19 and 25 is pulled out and the panel 26 is folded down upon its hinges 27 so as to project in the line of the table top 10 and rest upon bracing member 18, 19 and 25. Slidable panel 27a is next pulled out, slidably supported upon top 11, and held against lateral displacement therefrom by the bars 21 and 22. The head of the occupant will rest on the soft corrugated cushion 43 on panel 26, and his feet will rest upon panel 27a in extended position.

A suitable crank handle (not shown) is then grasped, and fitted with its socket against the polygonal wrench head 42 of the pinion rotating shaft 41, which is turned so as to rotate the pinions 40, which then begin to travel upon the teeth of the racks 39 at the same time.

As the pinions thus travel on the mentioned racks it is obvious that rollers 35 also travel on their tracks 36 and in doing so the coupler arms 28, 29 on each leg 32 and 33 move forwardly in the direction of the rigid legs 15 and 16. As these coupler arms are thus urged forwardly the lower pivoted ends of these arms rock the legs 32 and 33 upon their lower hinges 12a and 13a tilting them at an angle, which action takes place without the necessity of the coupler arms turning upon their pivot pins 30 because the two-point bearing of the roller and pinion on opposite sides of the track-rack, in each case, assures a perpendicular disposition of these couplers as the pin-

ions travel along in mesh with the racks. This is shown in dotted lines in Figure 1. But, as the legs 32 and 33 move forwardly they also move downwardly, and in doing so the rollers 35 will pull down upon the tracks 36, and, therefore, pull down also upon the false top 11 to which the tracks are secured. This tilts both the top 10 and 11 and bracing member 19, which has been extended to support the panel 26 in extended position, so the entire table top structure inclines downwardly, hanging down upon its hinges 12-13. In fact the entire length of the table, consisting of top 10 and front panel 26 in extended position and rear panel 27a also in extended position, will be tilted. As the table assumes such tilt or inclination, the head of the occupant will be lowered gradually to the desired degree of incline, and the feet will be elevated with respect thereto. This will usually relieve strain on and fatigue of muscles, nerves and internal organs of the body of the occupant and tend to induce correct posture. At the end of the rest period, rotations of the pinions is reversed so that the table top may be restored to initial horizontal position, and the occupant may rest in such position, if desired.

In the modified form of our invention, shown in Figures 4 and 5, the same results are accomplished in a different manner. Here the device not only serves the purpose of an inclinable posture table, also when not used for this purpose may be used as a hassock. The bottom hassock section is wedge-shaped, being a rectangular enclosure with a bottom and closed top. The top 43 constitutes an inclined table top supported upon the wedge-shaped sides 50 so that the rear part 53 is highest and the front part 52 lowest, in height. The corrugated cushion cover 51 covers the part 43. The other hassock section is also wedge-shaped, whose top 55, when this section is closed in surmounted relation upon the lower hassock section, becomes its bottom when the sections assume the open position, as at 11, 11a, shown in Figure 4. The upper hassock section tapers to a thin edge 57, has the sides 59 and highest part at its wall 58, which latter part, at its under edge, is hinged operatively to a pintle 54 so that this section may open and close upon the under section. The inclined top portion 56 of the last described hassock section is designated 56. When both sections assume the position where one is extended in front of the other with confronting inner parts 52 and 58, as in Figure 4, there will be a continuously beveled surface and wedge shaped structure presented to view, the top inclination of one section being continued in pitch onto the other section. The guide space 64 is formed by spacing a panel 60 below top inclined panel 63, so an extensible panel 65 may ride in and out of this space. Otherwise, the use and operation of the device is identical with what has already been described.

To close the two hassock sections, the narrower of the two wedge-shaped ones is folded up on its hinged pintle 54, which action also folds the corrugated cushion upon itself and closes the one section cover-like upon the other, after which the hook pivoted freely at 66 upon one section, is caught around the pin 68 on the other section 70 so the top sections may be closed, one upon the other. The straps 70 are fixedly secured at their upper ends and serve as a means in assisting in lowering and raising the body.

We do not mean to confine ourselves to the exact details of construction herein described, but

cover all variations falling within the scope of the appended claim.

We claim:

A device of the kind described comprising a frame including a pair of vertically extending fixed members at one end thereof, a table top pivotally mounted at one end thereof on the top of said members, a pair of collapsing members pivotally mounted at the bottom thereof on the other end of said frame, a gear rack secured to the bottom side of said table top and spaced downwardly therefrom, a coupling member pivotally mounted on the top of each of said collapsing members, including a pinion member engaging said gear rack and a roller member disposed above said gear rack and in rolling engagement therewith, and means for rotating said pinion member whereby, when said pinion member is rotated to effect the movement of said coupling members toward said fixed members, said collapsing members will be pivoted towards said fixed members to effect the downward inclination of the end of the table top removed from said fixed members.
